UNITED STATES PATENT OFFICE.

EDWARD FISH, OF CORTLAND, NEW YORK.

SHADE AND CURTAIN HANGER.

No. 926,181.

Specification of Letters Patent. Patented June 29, 1909.

Application filed May 16, 1908. Serial No. 433,294.

To all whom it may concern:

Be it known that I, EDWARD FISH, a citizen of the United States, residing at Cortland, in the county of Cortland and State of New York, have invented a new and useful Shade and Curtain Hanger, of which the following is a specification.

This invention relates to a combined shade and curtain hanger; and has for its object 10 to provide a simple, strong, efficient and economical hanger for the purpose designed which can be easily attached to the top of a window frame and afford support for a curtain pole and for one or more shade rollers. 15 A further object of the invention pertains to the means for supporting the shade roller brackets whereby they may be quickly adjusted to suit a shade roller of any length, or two or more shade rollers, if such should 20 be desired, may be carried by said supporting means in adjustable brackets.

With these and other objects in view the invention consists of the novel combination and arrangement of parts hereinafter described and claimed, and illustrated in the accompanying drawing forming a part of this specification, in which—

Figure 1 is a perspective view of the improved shade and curtain hanger; Fig. 2 an 30 end view of the same; and Fig. 3 a cross sectional view of the invention on the line 3—3 of Fig. 1 showing it attached to a window frame.

Similar reference numerals are used for 35 the same parts in all the figures.

In the drawings, 1 indicates a flat bar or strip of metal the longitudinal edges of which are bent over on the same side of the bar or strip to form guide-ways 2 for two or 40 more shade holding brackets 3 which are adapted to slide longitudinally therein, but prevented from a too free movement by frictional contact of the base 4 of the brackets with the side and guide-ways 2 of the bar or 45 strip 1. Countersunk holes 5 are bored in the bar or strip 1 for the fastening screws 6 which enter the window frame as shown. The shade holding brackets 3 here represented are like those in common use, made of 50 stamped sheet metal with bases 4 and bodies 7 perpendicular thereto in the outer ends of which are openings 8 for receiving the projecting pins on the ends of a shade roller. At each end of the bar 1 a forwardly 55 projecting arm 9 is fastened by a rivet 10, the lower end of which arm enters the bottom

guide-way 2 and is steadied thereby. Above the rivet 10 the arm is curved gracefully forward for a sufficient distance and then bent downwardly to form a substantially 60 semi-circular rest or seat 11 for a curtain pole 12 which extends from one arm 9 to the other.

A shade and curtain hanger constructed as above may extend across a single window 65 frame and have adjustable brackets for one shade, or the holder may be made of a length sufficient to extend across two or more windows and be provided with a pair of shade roller brackets for each window and a curtain pole arm at each end only. It will also be noted that by driving a few screws through the strip 1 into the window frame or frames all the necessary shade brackets and curtain pole arms are fastened thereto and in correct 70 relation to one another, or easily placed so by sliding the shade brackets which may be moved from one end of the bar or strip 1 to the other.

Instead of depending on the frictional 80 contact of the base 4 with the bar or strip for holding the shade brackets in position, a screw 13 may be threaded in said base to bear against the bar when turned.

What is claimed is:—

A shade and curtain hanger comprising a flat bar provided with countersink perforations, and having its longitudinal edges turned over to form continuous upper and lower guide-ways extending throughout the 90 entire length of the bar, fastening means passing through the aforesaid perforations, and extending flush with the face of the bar, adjustable shade brackets fitting on the face of the bar, and extending at their upper and 95 lower ends into the guide-ways, means for holding the shade brackets in adjustment, and a curtain-pole supporting arm secured to the face of the bar, and extending at one end into the lower one of the aforesaid guide-ways, the other end of said arm extending in 100 front of and outside of the upper guide-way, and having a forward bend terminating in a curtain-pole seat.

In testimony that I claim the foregoing as 105 my own, I have hereunto affixed my signature in the presence of two witnesses.

EDWARD FISH.
